UNITED STATES PATENT OFFICE

OTTO KRESS, OF APPLETON, WISCONSIN

METHOD OF MARKING AND PRODUCING DESIGNS ON PAPER

No Drawing.

Application filed June 5, 1929. Serial No. 368,744.

This invention relates to a new and improved method of marking and producing designs on paper.

One of the objects of my invention is to provide an improved method of marking or producing designs on paper through the use of a reducing agent applied to the paper by printing or marking the same thereon with a roller carrying the reducing agent and engaging the paper during the production stage of the paper and at a time just prior to the complete drying of the paper so that the reducing agent may be dried during the completion of the drying of the paper itself.

Another object of my invention is the provision of an improved method for marking or producing designs in what is known as "kraft" paper, by applying a solution of a reducing agent which has the property of reducing the coloring compounds present in the paper and preferably applying this reducing compound to the web of paper after it has been partially dried, or dried to a point whereby the moisture contents thereof are about 30% to 40%, it being essential that the paper be sufficiently dry so that the solution will not spread when it is transferred to the web of paper by a marking roll, or the like.

A still further object of my invention is the provision of an improved method for marking or producing designs in paper through the medium of the application of sodium bisulphite, or any similar compound carrying a sulphur dioxide radical and applying this solution to the web of paper through the medium of printing or marking rolls, the compound creating a bleaching action to produce a design in the paper. This can be carried out either as a separate operation or during the drying of the paper on the machine, so that the manufacturing and marking of the paper can be carried out in one operation.

As stated in the objects, my improved method for marking or producing designs on what is well known in the trade as "kraft" paper, can be carried out by the use of sodium bisulphite or any compound carrying a sulphur dioxide radical such as sodium hydro-sulphite or any bisulphite, such as a solution

of calcium bisulphite which has the property of reducing the coloring compounds present in the kraft pulp, or paper.

The well known "kraft" paper is of a natural reddish or brown color, and by using a compound as disclosed above and applied to the paper, a bleaching action will result so that the paper can be readily marked with any desired design. The preferred method of producing a design on the paper is to apply a solution of from 1% to 5% of sodium bisulphite to an engraved or marking roller and then engaging this roller with the web of paper after it has been partially dried or at such a time as the moisture contents of the paper will run about 30% to 40%. It is, however, essential that the web of paper be sufficiently dried so that the solution of the bisulphite will not spread when it is transferred to the web of paper from the marking or printing roller.

After the solution has been transferred to the partially dried web of paper, the rest of the moisture in the sheet and the moisture from the solution of sodium bisulphite is evaporated on the balance of the driers, during the manufacture of the paper, before the paper is wound on a reel or cut into sheets according to standard practice at the dry end of the paper machine.

It will be noted from the foregoing that paper is made on a variety of machines, but in all cases the wet web of paper after it has been formed on what is known as the wet end of the paper machine, is dried by passing it over suitable rollers and it will be readily apparent that at a predetermined step in the drying operation of the paper, the marking roll to which a solution of sodium bisulphite has been applied can be engaged with the paper during the drying process.

A suitable design or marking can also be produced in the paper by coloring the sheet or paper in the usual manner as is well known in the art and then discharging some of the color by printing the sheet with a solution of bisulphite in the manner described above. In printing designs on colored sheets, the sodium bisulphite acts as a reducing agent and reduces the aniline dye stuffs contained

within the paper to produce colorless or lighter colored compounds, thereby producing a marking or design on a colored background.

5 It will be apparent from the foregoing that I have provided a simple and inexpensive method of marking or producing designs on colored paper, but preferably what is known on the market as "kraft" paper which is ordinarily of a natural reddish or brown color and wherein designs can be quickly and readily produced thereon by applying to the paper, through the medium of a marking or printing roller, a reducing solution which 10 will create a bleaching action on the paper

The marking or design of the paper can be done as a separate operation or on the paper machine towards the dry end of the machine as described. If the marking is to 15 be done as a separate operation the dry paper is printed with a water solution of a compound containing a sulphur dioxide radical the preferred chemical being sodium bisulphite. The printing is done by suitable engraved or marked rolls, the paper being fed 20 in web form from a suitable roll through the printing machine. The excess of water used to dissolve the bleaching compound is evaporated on suitable dryers.

25 30 While I have described the application of a solution as from 1% to 5% of sodium bisulphite, it will be apparent that the proportion may be varied according to the type of paper to which the solution is being applied, and also according to the design required.

35 40 While I have shown and described the preferred embodiment of my invention, it will be apparent from the foregoing that slight changes may be made in the steps when putting the invention into practice without departing from the spirit of the same or the scope of the appended claims.

I claim:

45 1. That step in the method of marking paper in a predetermined design, which consists in applying to a damp sheet web of paper, a bleaching compound in predetermined areas, whereby said areas will be 50 bleached a lighter color than the body of the sheet.

55 2. That step in the process of marking paper in a predetermined design, which consists in applying sodium bisulphite to a roller bearing a predetermined design, and applying the roller to a damp web of paper, as the paper is being dried on the Fourdrinier paper machine.

60 In testimony that I claim the foregoing I have hereunto set my hand at Milwaukee, in the county of Milwaukee and State of Wisconsin.

OTTO KRESS.
